US00D708949S

(12) **United States Design Patent**
Crawford et al.

(10) **Patent No.:** **US D708,949 S**
(45) **Date of Patent:** **** Jul. 15, 2014**

(54) **CAP FOR A CONTAINER**

(75) Inventors: **John C. Crawford**, Mahopac, NY (US);
Christopher Hart, Chicago, IL (US);
Stacy Castro, Chicago, IL (US)

D286,984 S 12/1986 Durand
D329,383 S 9/1992 Boucheron
D336,237 S 6/1993 Rossi
D337,275 S 7/1993 Tutssel
D338,828 S 8/1993 Segati

(Continued)

(73) Assignee: **Colgate-Palmolive Company**, New York, NY (US)

FOREIGN PATENT DOCUMENTS

(**) Term: **14 Years**

AU 122034 11/1994
AU 128474 10/1996

(Continued)

(21) Appl. No.: **29/424,000**

(Primary Examiner — Robert M Spear

(22) Filed: **Jun. 7, 2012**

(74) Attorney, Agent, or Firm — Judy W. Chung

(51) LOC (10) Cl. **09-07**

CLAIM

(52) U.S. Cl.

The ornamental design for a cap for a container, as shown and described.

USPC **D9/449**

DESCRIPTION

(58) **Field of Classification Search**

USPC D9/435, 446, 447, 449, 454, 516, 529,
D9/530, 537-546, 550-552, 563, 565, 574,
D9/575; 215/220; 220/660, 669, 670, 675;
206/534

See application file for complete search history.

FIG. 1 is a front perspective view of a cap for a container according to the new design, the cap being shown in an opened state;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, the cap being shown in an opened state;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

All broken lines shown in the drawings are for environmental purposes only and form no part of the claimed design.

1 Claim, 8 Drawing Sheets
